PERMANENT HAIR WAVING DEVICE

Michael Gialafos, New York, N. Y.

Application February 18, 1936, Serial No. 64,425

4 Claims. (Cl. 132—36)

This invention relates to new and useful improvements in a permanent hair waving device for forming a spiral wave.

The invention contemplates the construction of a device as mentioned which is characterized by a rigid base plate for resting flat against the head and having an opening cut in one side through which a lock of hair may pass, clamps associated with said base plate for holding the base portion of the lock of hair in a desirable position, and a mechanism for curling the hair upon a mandrel projecting from the top face of said base.

A further object of the invention is the association of a cylindrical heating element with the curled hair to produce the required heat necessary in permanent waving.

Furthermore, the invention particularly proposes to utilize a heating element which is operative chemically.

A further object of the invention resides in the particular arrangement of the clamps previously mentioned. It is proposed to mount one of the clamps across the opening in the side of the rigid plate for clamping the hair, and to arrange the second clamp for holding the hair against the lower portion of the mandrel and adapted to be opened after the hair is curled on the mandrel, and to clamp the lower portion of the cylindrical heating element to hold it in operative position.

Still further, the invention contemplates a construction which is capable of using a cylinder normally engageable over the mandrel and having an opening to receive the lock of hair and adapted to be rotated along the mandrel to wind the hair on the mandrel.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a permanent hair waving device constructed according to this invention and shown in the act of supplying the heat necessary for the permanent waving.

Fig. 2 is a horizontal sectional view taken on the line 2—2 of Fig. 1.

Fig. 3 is a perspective view of the rigid base plate with the mandrel, and the clamps, illustrated per se.

Fig. 4 is a perspective view of the cylinder used for curling the hair.

Fig. 5 is an elevational view illustrating the cylinder in use.

Fig. 6 is a perspective view of the cylindrical heating element.

Fig. 7 is a sectional view taken on the line 7—7 of Fig. 5.

The permanent hair waving device, according to this invention, comprises a rigid base plate 10 adapted to be engaged flat against the scalp, and formed with an opening 11 in one side through which a lock of hair 50 may be passed. A mandrel 12 rigidly projects from the top face of the base plate 10 at the center thereof. A hair clamp 13 is mounted upon the plate 10 and is extendible across the opening 11 for clamping the lock of hair at the roots to hold the base plate on the head. A second clamp 14 is arranged upon the top face of the base plate 10 and is adapted to hold the lock of hair which passes through the opening 11 about the base of the mandrel 12. These clamps prevent one's hair being pulled when it is wound upon the mandrel, as herein-after fully described.

A heating element 15 is engageable over the lock of hair after it is wound upon the mandrel. The second clamp 14 is adapted to be opened and re-clamped to hold the heating element 15 in position. The hair is wound upon the mandrel by the use of a cylindrical member 16 having an opening 17 in one end thereof adapted to receive the lock of hair. When the cylindrical member 16 is rotated along the mandrel it will wind the hair in a curl, as clearly shown in Fig. 1.

The base plate 10 is made of heat insulating material and serves to prevent steam which is generated during the hair waving process from reaching the scalp and causing burns. The mandrel 12 is in the form of a solid aluminum rod, though it may be of other construction if need be.

The hair clamp 13 operates in a lateral groove 18 formed in the edge of the base plate 10. It is pivotally held at one end by a pintle 19. It is adapted to be extended across the opening 11 and into the groove 18. It has a prong 20 at the free end engageable selectively with depressed areas 21, as clearly shown in Fig. 2. This is the closed position of the clamp. The clamp is also provided with a handle 22 by which it may be conveniently operated.

The clamp 14 is constructed of a pair of pivotally connected jaw sections 14a and 14b. These sections are pivotally connected by a pintle 23 mounted on the base plate 10. A washer 24 is interposed between the clamp and the plate 10 to hold the clamp slightly spaced from the top face of the base plate, as clearly shown in Fig. 1. This provides a passage through which the lock of hair, indicated by reference numeral 50, may pass. Each of the jaws 14a and 14b is of arcuate shape so that when they are close together, as shown in Fig. 2, they encircle the mandrel 12. To facilitate moving the jaws, each of the jaws is provided with a projecting handle 25. The jaw 14b is provided with a plurality of apertures 26 which is adapted to be engaged by the front end 27' of a pivoted element 27 mounted on the jaw 14a. The jaw 14a is formed with an opening through which the front end 27' extends to be engageable selectively with the apertures 26. The element 27 is pivotally supported on lugs 28 and is normally urged into a closed position by a spring 29. This spring acts between the rear end of the member 27 and the jaw 14a.

The cylindrical member 16 is adapted to slidably and rotatively engage on the mandrel 12. The lock of hair may be engaged up through the open end 16' of the cylindrical member and through the side opening 17. Then, when the side cylindrical member is rotated and moved along the mandrel the lock of hair 50 will be formed into a curl, indicated by the reference numeral 50' in Fig. 1.

35 The cylindrical heating element 15 comprises an outer cylindrical paper jacket 15' holding a cylindrical chemical cartridge 30. This chemical cartridge consists of an outer cylindrical casting 30a, an inner perforated cylindrical casing 30b, and internal chemical 30c. A porous and absorbent cylindrical member 30d, such as felt or cloth, engages within the part 30b to prevent the chemical from falling out through the openings.

45 The chemical 30c is preferably a composition of elements capable of slowly heating when moistened and reaching a desired temperature necessary in permanent hair waving. For example, the following formula would be satisfactory:

	Parts
Pumice	20
Chrome alum	2
Potassium chlorate	2
Ferric chloride	2
55 Metal magnesium (powder)	2

In order to make a good permanent wave it is necessary that the hair be moistened with a waving solution. A satisfactory waving solution 60 for the type of heater called for in this invention is given by the following formula:

	Per cent
Soft soap	3.00
Ammonium chloride	0.50
65 Essence lemon	0.15
Gelatin	1.00
Glycerine	1.50
Water	93.85

70 The operation of the device is as follows: A lock of hair is straightened out and passed through the opening 11 of the plate 10. The plate is placed against the head. Then the clamp 13 is closed so as to attach the plate 10 upon the head. The lock of hair is turned once around

the bottom of the mandrel 12 and the clamp 14 is closed to hold the hair at the roots about the mandrel.

The cylindrical member 16 is engaged over the mandrel and the lock of hair passed through the opening 17. The cylindrical member 16 is turned to curl the hair on the mandrel. The end of the curl may be tied with a string 50a to the mandrel, or an elastic may be used. In fact, the curl may be held in any suitable manner in the desired position. The cylindrical heat element 15 is then engaged over the curl of hair. It is placed completely on the curl and is held in position by the clamp 14 which must first be opened to allow the end of the heat element to extend down a sufficient distance. The clamp is closed and serves to hold the heating element in position.

The heating element 15 is moistened prior to its engagement upon the curl. The curl is treated with the waving solution. The heat generated by the heating element will permanently wave the curl of hair.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim and desire to secure by United States Letters Patent is:—

1. In a permanent hair waving device a rigid base plate for resting flat against the head and having an opening cut in one side, a mandrel projecting from the top face of said base, a hair clamp mounted on said plate and extending over the said opening for clamping a lock of hair at the roots to hold said base plate on the head, a second clamp on the top face of said base plate for holding said lock of hair at the root ends about the base of said mandrel, and a cylindrical heating element engageable over said lock of hair when wound spirally on said mandrel, and said second clamp also being adapted to clamp and hold said cylindrical heating element.

2. In a permanent hair waving device a rigid base plate for resting flat against the head and having an opening cut in one side, a mandrel projecting from the top face of said base, a hair clamp mounted on said plate and extending over the said opening for clamping a lock of hair at the roots to hold said base plate on the head, and a cylindrical heating element engageable over said lock of hair when wound spirally on said mandrel, and said second clamp also being adapted to clamp and hold said cylindrical heating element, said hair clamp comprising a member pivotally mounted at one end and engageable in a groove across the opening in said base plate and adapted to be held at the free end in desired fixed positions.

3. In a permanent hair waving device, a rigid base plate for resting flat against the head and having an opening cut in one side, a mandrel projecting from the top face of said base, a hair clamp for clamping a lock of hair at the roots to hold said base plate on the head, a second clamp on the top face of said base plate for holding said lock of hair at the root ends about the base of said mandrel, and a cylindrical heat-

- ing element engageable over said lock of hair when wound spirally on said mandrel, and said second clamp also being adapted to clamp and hold said cylindrical heating element, said second clamp comprising a pair of arcuate jaws pivotally connected at one of their ends by a pin mounted on said base plate, said jaws being slightly spaced from the top face of the base plate by a suitable washer. 5
- 10 4. In a permanent hair waving device, a rigid base plate for resting flat against the head and having an opening cut in one side, a mandrel projecting from the top face of said base, a hair clamp mounted on said plate and extending over the said opening for clamping a lock of hair at
- 15 the roots to hold said base plate on the head, a second clamp on the top face of said base plate for holding said lock of hair at the root ends about the base of said mandrel, and a cylindrical heating element engageable over said lock of hair when wound spirally on said mandrel, and said second clamp also being adapted to clamp and hold said cylindrical heating element, said cylindrical heating element comprising a tubular jacket housing a tubular chemical which is 10 adapted to become hot upon the application of water and said jacket being the portion adapted to be clamped by said clamp. 5
